UNITED STATES PATENT OFFICE.

FRANK KUHN AND JAY A. HAND, OF DETROIT, MICHIGAN, ASSIGNEES TO AMERICAN ELECTRICAL HEATER COMPANY, OF DETROIT, MICHIGAN, A CORPORATION OF MICHIGAN.

DESIGN FOR AN ELECTRIC COOKER.

52,327.

Specification for Design.

Patented Aug. 27, 1918.

Application filed February 21, 1918. Serial No. 218,584. Term of patent 14 years.

To all whom it may concern:

Be it known that we, FRANK KUHN and JAY A. HAND, both citizens of the United States of America, both residing at Detroit, in the county of Wayne and State of Michigan, have invented a certain new, original, and ornamental Design for Electric Cookers, of which the following is a specification, reference being had therein to the accompanying drawings, forming part thereof, in which the figure is a perspective view.

We claim:

The ornamental design for an electric cooker, substantially as shown.

FRANK KUHN.
JAY A. HAND.
